Patented Oct. 29, 1974

233,385

WALL MOUNTABLE BRACKET

Harvey L. Friedman, 6361 Fairhaven Road,
Mayfield Heights, Ohio 44124

Filed Sept. 15, 1972, Ser. No. 289,689

Term of patent 14 years

Int. Cl. D6—99

U.S. Cl. D6—114

FIG. 1

FIG. 2

FIG. 3

FIG. 4

FIG. 5

FIG. 6

FIG. 1 is a front elevational view of a wall mountable bracket embodying my new design.

FIG. 2 is a right side elevational view of the wall mountable bracket.

FIG. 3 is a top plan view of the wall mountable bracket.

FIG. 4 is a left side elevational view thereof.

FIG. 5 is a bottom plan view thereof.

FIG. 6 is a back elevational view thereof.

I claim:

The ornamental design for a wall mountable bracket, as shown.
